REPEATING GUN

Charles E. Johnson, Muskegon, Mich.

Application May 7, 1934, Serial No. 724,260

3 Claims. (Cl. 42—2)

This invention relates to repeating guns and is concerned with a novel improvement therein relating to the operation of the mechanism which ejects the exploded cartridge shell and 5 also reloads the gun and places it in firing condition.

In repeating rifles and shotguns it is common to have a magazine located beneath and parallel to the barrel in which a number of cartridges 10 are held. An operating member is slidably mounted on the magazine and is movable lengthwise thereof and has a bar connected thereto which extends rearwardly into an intermediate housing between the barrel and stock of 15 the gun. Reciprocation of the operating member mounted on the magazine rearwardly serves to eject a cartridge which has been fired, and return movement forwardly of the operating member moves a new cartridge into the chamber at the rear end of the barrel.

It is a primary object and purpose of the present invention to mount the operating member on the magazine for slidable movement lengthwise thereof and interpose mechanism between it and 20 the bar which ejects the exploded cartridge and inserts a fresh cartridge so that the outward or forward movement of such operating member effects ejection of the exploded cartridge, and rearward movement of said operating member 25 inserts the new cartridge into the cartridge chamber at the rear end of the barrel. By so doing the operating member which is of a size and shape to be grasped by the hand is located at the rear directly in engagement with the intermediate housing above referred to and is in a position for a natural 30 grasping thereof by one of the hands for firing the gun, and not at an outer position between the ends of the barrel as has been the previous 35 position thereof. At the same time the unsightly gap between said operating member and the housing which houses the cartridge control mechanism is completely covered presenting a much better appearance and one which the gun 40 will have nearly all of the time as the normal position of such operating member, said operating member never being out of such position except momentarily when it is moved forward before again being moved to the rear 45 in the operations of ejecting an exploded cartridge and inserting a new cartridge into place.

An understanding of the invention may be had from the following description taken in connection with the accompanying drawing in 50 which,

Fig. 1 is a side elevation of a gun made in accordance with my invention.

Fig. 2 is a fragmentary enlarged horizontal section on a plane between the barrel and the magazine looking upwardly against the barrel. 5

Fig. 3 is a transverse vertical section substantially on the plane of line 3—3 of Fig. 2.

Fig. 4 is a transverse section substantially on the plane of line 4—4 of Fig. 1, looking in the direction indicated by the arrow, and 10

Fig. 5 is a fragmentary vertical section showing in side elevation the mechanism between the operating member and the cartridge ejecting bar.

Like numerals refer to like parts in the different figures of the drawing.

In the drawing, the gun shown is a repeating shotgun having a barrel 1, stock 2, magazine 3 of tubular form located below and parallel to the barrel and an intermediate housing 4 between the stock and the barrel for housing the cartridge ejecting and inserting mechanism of the gun, in one side of which is a gate 5 through which the exploded cartridges are ejected. 20

The operating member 6, preferably of wood, for controlling and securing the ejection of an exploded cartridge and the taking of a fresh cartridge from the magazine and placing it in the cartridge chamber at the rear end of the barrel 30 embraces the magazine 3 at its sides. It is substantially of a U-shaped form in cross section, the legs of which are thickened at their upper ends so as to pass inwardly partially over the magazine and extend upwardly to the lower side 35 portions of the barrel 1 (see Fig. 2). At the rear end of the operating member 6, the sides thereof are reduced in thickness so that at the inner position, shown in Fig. 1, they may cover partially the front end of the metal housing member 4. These thinner sides are shown at 6a 40 in Fig. 4.

The barrel and the tubular magazine 3 in practice are spaced a short distance apart, approximately or substantially one-eighth of an 45 inch. With my invention a short stud 7 is formed at the lower side of the barrel at a point where it will always be covered by the sides of the member 6 and on this stud a pinion 8, preferably stamped from flat metal, is mounted 50 for free rotative movement.

In one upwardly extending leg of the member 6 (at the right hand side of the gun) at the inner side thereof a rack 9 is embedded and permanently secured. This rack is made from a flat 55

bar of metal, consecutive openings being made therethrough spaced apart short distances from each other so that the teeth of the pinion may enter such openings.

5 At the inner side of the other upwardly extending leg of the member 6 a guide groove is cut. A flat bar 10 passes slidably through the front end of the housing 4 and its movements serve to operate mechanism for ejecting an exploded cartridge and inserting a new cartridge into the cartridge chamber. The details of such mechanism are not disclosed as it is old and well known. The bar 10 on which is formed the rack 11 extends forward and is received in the 10 guide groove in said opposite upwardly extending leg of the operating member 6 and at its forward portion is made into a rack 11 similar to the rack 9, that is, with spaced apart consecutive openings cut therethrough to receive the 15 teeth of the pinion 8.

In operation it is evident that with the operating member 6 in the position shown in Fig. 1, which position it occupies at the time a cartridge is fired, forward sliding movement of said member 6 on the magazine 3 moves the rack 9 forward and rotates the pinion 8 which, engaging with the rack 11, moves the bar 10 in an opposite direction or rearwardly into the housing 4. Such rearward movement of the 20 bar 10 operates the mechanism for ejecting the exploded cartridge.

On the return rearward movement of the operating member 6, the bar 9 moves with it to the rear and bar 10 moves in the opposite direction forward in the guide groove made at the inner side of the opposite upwardly extending leg of member 6. Such forward movement of bar 10 serves to insert a new cartridge taken from the magazine into the cartridge chamber at 25 the rear end of the barrel 1 and closes the mechanism and the gun is ready for firing.

It is apparent from this construction that the operating member 6 which is moved forward and then back on the magazine 3 for cartridge ejection and insertion, instead of being located at a forward position on the magazine and with an uncovered gap between the housing 4 of the rear end of said operating member 6 is, in normal operative position for using the gun, back against 30 and in fact partially covers the forward end portion of the metal housing 4. In such position the gun is ready to be fired and the member 6 is in a far better and more desirable position to be grasped by the hand for holding and 35 steadyng the gun for firing than if it was moved forward as is now substantially universal in all repeating fire arms of either the usual rifle or shotgun type.

From the foregoing the construction embodying 40 my invention is readily understood. It is realized that other mechanism for operating the bar 10 by the member 6 in a reverse direction to the movements of the operating member 6 may be devised and therefore I do not wish to be restricted to the specific form of mechanism shown. It is however, a practical mechanism and one which is economical to make and 45 readily installed.

It is evident from the operation described 50 that the operating member 6 when moved forward and then back to the position shown in Fig. 1 results in the last movement of the arm or hand of the person using the gun, pressing the same against his shoulder instead of pushing 55 it away from the shoulder as in previous op-

erations wherein the operating member was first moved to the rear and then forward in completing reloading. There is thus accomplished one of the main objects of the invention and that is that the hunter having fired the gun 5 pushes the operating member 6 forward first and then returns it to the rear automatically pressing the gun against his shoulder whereby he is instantly ready to fire the same and at the same time his hand is in the most suitable 10 and most desirable position for steadyng and holding the gun secure against movement.

The invention is defined in the appended claims and is to be considered comprehensive of all forms of structure coming within their 15 scope.

I claim:

1. In a repeating gun having a barrel, stock, housing for reloading control mechanism disposed between the barrel and stock and an elongated magazine for holding cartridges located underneath and parallel to said barrel, of a reciprocating bar extending into said housing and in front of the same and parallel to said barrel and magazine, an operating member 25 of substantially U-shape in cross section mounted on said magazine, one leg of said operating member having a groove guide therein in which the forward end portion of said bar is located, and means carried by the other leg 30 of said operating member and said barrel and between the magazine and said barrel for reciprocating the bar upon reciprocation of said operating member and in directions opposite to the movements of said operating member. 35

2. In a repeating gun having a barrel, a stock, housing for cartridge controlling mechanism, and a tubular magazine located underneath and parallel to the barrel and extending forward from said housing, of an operating member slidably mounted on the magazine and movable from a rear position in which its rear end engages said housing to a forward position on the magazine and back to original position, a reciprocable bar extending at its rear end portion 40 into said housing and at its front end portion in front of the housing and within said operating member, means mounted between the barrel and magazine and driven by said operating member engaging said bar to reciprocate the same in a rearward direction on forward movement of the operating member and in a forward direction on rearward movement of the operating member to its original position. 45

3. In a repeating gun having a barrel and an elongated magazine for holding cartridges, an operating member of substantially U-shape in cross section slidably mounted on and embracing said magazine, said member having spaced apart legs extending upwardly into substantial contact with the barrel, one leg of the operating member at its inner side having a guide groove therein, a bar located in said guide groove having a rack formed at its forward portion, a stud between adjacent sides of the barrel and magazine carried by one of said members, a pinion rotatably mounted on the stud having one side engaging said rack, and a second rack permanently secured to and at the inner side of the other leg of said operating member with which the opposite side of the pinion is in engagement, as and for the purposes specified. 55

CHARLES E. JOHNSON.
